Specification for Design.

Patented May 6, 1913.

Application filed January 14, 1913. Serial No. 742,058. Term of patent 7 years.

To all whom it may concern:

Be it known that I, GEORGE E. FAHYS, a citizen of the United States, and a resident of Glen Cove, in the county of Nassau and State of New York, have invented a certain new, original, and ornamental Design for Backs for Mirrors, Brushes, or Similar Articles, of which the following is a specification.

In the accompanying drawing, Figure 1 is a plan view of the back of a brush or mirror

having my design applied thereto. Fig. 2 is a sectional view taken on the line 2—2 of Fig. 1, looking in the direction as indicated by the arrow.

I claim:

The ornamental design for a back for a mirror, brush, or similar articles, as shown.

GEORGE E. FAHYS.
